R. C. NEWHOUSE

CRUSHER LUBRICATING SYSTEM

Original Filed Jan. 3, 1921

UNITED STATES PATENT OFFICE.

RAY C. NEWHOUSE, OF WAUWATOSA, WISCONSIN, ASSIGNOR TO ALLIS-CHALMERS MANUFACTURING COMPANY, OF MILWAUKEE, WISCONSIN, A CORPORATION OF DELAWARE.

CRUSHER-LUBRICATING SYSTEM.

Original application filed January 3, 1921, Serial No. 434,493. Divided and this application filed April 13, 1922. Serial No. 552,393.

To all whom it may concern:

Be it known that RAY C. NEWHOUSE, a citizen of the United States, residing at Wauwatosa, in the county of Milwaukee and

5 State of Wisconsin, has invented a certain new and useful Improvement in Crusher-Lubricating Systems, of which the following is a specification.

10 This invention relates in general to crushers and more particularly to lubricating systems for crushers. It may be applied with particular advantage in crushers of the gyratory type.

15 One of the objects of the invention is the provision of an efficient lubricating and oil circulating system which is not readily susceptible to failure and is moreover accessible for repairs. Ancillary to an efficient lubricating and oil circulating system a further object is the provision of means whereby dust may be effectively prevented from entering the lubricating oil and particularly the eccentric bearings of the crusher.

20 Other objects will appear hereinafter as the description of the invention proceeds.

25 The novel features of the invention will appear from this specification and the accompanying drawing forming a part thereof and disclosing one embodiment of said invention and all these novel features are intended to be pointed out in the claims.

30 Fig. 1 is a vertical sectional view of a crusher embodying the features of the invention.

35 Fig. 2 is a fragmentary view taken along the line II—II of Fig. 1 and shows a pump in the oil circulating system of the crusher and the manner of driving and mounting the same.

40 Fig. 3 is a fragmentary detail view of one end of the pump shown in Fig. 2.

45 The crusher illustrated in Fig. 1 is of the type described and broadly claimed in an application of R. C. Newhouse Serial No. 434,493, filed Jan. 3, 1921, of which this application is a division, and comprises a top shell 1 and a bottom shell 2 adapted to support the top shell. A spider 3 is provided for carrying the crusher shaft 4 and parts rotating therewith by means of the suspension collar 5 and the ball and socket 6, 7, comprising a suspension bearing. The crusher shaft 4 is provided with a suitable

crusher head 8 which in conjunction with the concaves 9 which line shell 1, coact in the well known manner to crush the material put into the crusher.

55 With the shaft 4 is associated an eccentric 10 having an inner bearing-surface 11 cooperating with the shaft and an outer bearing-surface 12 cooperating with the outer bearing 13. The bearing 13 is supported by a member 14. The bearing supporting member 14 is in turn supported from the shell by a number of strut members one of which, 19, is shown in Fig. 1. The member 14 is in addition supported as appears in the parent application, supra, to resist the great strains put upon it by the eccentric when the crusher is in operation.

60 The eccentric has a bevel gear 20 operatively associated therewith, as by means of the key 21, and the weight of this gear and the eccentric are carried by a wearing ring 22. The wearing ring 22 is supported by 65 a bottom plate 23 which may be bolted to and supported by the bottom shell of the crusher. The bottom plate is here shown as provided with a transversely extending flanged portion 24 for supporting the wearing ring 22 and a transversely extending flanged portion 25 by means of which the bottom plate may be fastened to the bottom shell.

70 The gear 20 is provided with a cover plate 26 which has a downwardly opening central recess 27 with which communicate radial 75 passages 28 having openings 29 in the upper side of the plate. While two radial passages are here shown, any desired number 80 may be utilized. The purpose of the recess and radial passages will be hereinafter set forth.

75 The gear 20 is here shown as driven by a bevel pinion 30 associated with a crusher driving shaft 31. This driving shaft is supported by a bearing 32. A pump 33 which may be of the rotary gear type is mounted in the housing of the bearing 32. This pump is provided with a shaft having ends 34, 35 extending in opposite directions out of the casing of the pump. A pinion 36 is adapted to be keyed to either the end 34 or the end 35 of the pump shaft. The pinion 36 is here shown as driven by a gear 37 rigidly associated with the driving shaft 31. The pump casing is provided with a

cylindrical portion 38 adapted to be journaled in a hole 39 in a wall 40 forming part of the bearing housing. The other end of the pump casing projects through a hole 5 41 in a wall 42 also a portion of the bearing housing. The walls 42 are surmounted by a roof 43 which together form a housing for the pump. The end of the pump casing which projects through the wall 42 is provided with a flange 44 having holes 45 through which stud bolts are adapted to pass into the wall 42 whereby the pump may be fastened. The suction side of the pump is connected by means of a pipe 46 10 through the wall 25 of the bottom plate to the annular well formed by the transverse portions or walls 24, 25 of the bottom plate and the gear 20. The discharge side of the pump is connected by means of a pipe 15 47 to the central portion of the bottom plate so as to communicate with the oil well formed by the central portion of said plate.

In order to prevent entrance of dust and other foreign material into the eccentric bearing surfaces and the lubricating oil, a bonnet 75 is provided. This bonnet is provided with a cylindrical portion 76 internally telescopically associated with the eccentric 10. The bonnet is provided with 20 a transverse flange 77 extending over the outer bearing member 13. The outer bearing member may, to the end that the entrance of foreign material will be more effectually prevented, be also provided with an inwardly extending flange 78. In order to prevent the entrance of foreign material between the cylindrical portion of the bonnet and the crusher shaft 4, a dust ring 79 surrounding the said shaft 4 is provided 25 and is formed to extend over said cylindrical portion 76. The bonnet may be rigidly associated in any desired manner with the eccentric and is preferably not in frictional engagement with any of the associated parts, thus reducing wear.

In order to provide for the passage of oil as between the inner and outer bearing surfaces 11, 12 of the eccentric any number of oil passages 80, 81 may be provided. 30 In order to provide for any excess of oil at the upper end of the eccentric and to prevent the overflow thereof onto the bearing support 14, the overflow pipe 82 is provided. The upper end of the pipe passes through 35 the upper end of the outer bearing 13 and the lower end passes through one of the struts 19 where any oil passing through said pipe is discharged onto the surface of the gear 20.

60 The operation of the lubricating system as related to the illustrated crusher is as follows:

The rotation of the crusher driving shaft in a predetermined direction causes the operation of the pump 33 by means of the 65 gear 37 and the pinion 36. It may be stated that the direction of rotation of the pinion 36 should always be the same, the pump being of the gear type and irreversible. The operation of the pump causes oil to 70 be drawn through the pipe 46, through the pump, and forced through the pipe 47 into the well formed by the central portion of the bottom plate 23. Some of this oil is forced up and out between the wearing ring 75 22 and the gear 20 thus affording efficient lubrication for these parts. The major portion of the oil pumped into the central oil well passes into the recess 27 and as the cover plate 26 is being rotated by the gear 75 29 the oil in question will be thrown out through the passages 28 by centrifugal force and will be expelled from the openings 29. The pressure of the centrifugal pump will 80 thus be added to that of the gear pump 85 and oil emerging from the openings 29 will be forced between the crusher shaft and the inner bearing 11 of the eccentric, up between these surfaces to and through the 90 passages 80, 81, down between the outer bearing surface of the eccentric and the bearing 13, into the gear 20. The inside of the gear 20 will ordinarily not be filled with oil inasmuch as the latter will be thrown up on the inside surface of the 95 gear by centrifugal force and from thence over the top thereof. From there the oil drops into the annular well formed by the transversely extending walls 24, 25 from where it again enters the pipe 46. If the 100 space at the top of the outer bearing surface of the eccentric and the bearings 13 should become full of oil, the excess will be discharged through the pipe 82 onto the gear 20, as has already been pointed out.

It is desirable that it be possible, for various reasons, to change the direction of rotation of the crusher driving shaft. Inasmuch as the shaft of the pump 33 must rotate in the same direction, means must be 110 provided whereby this result may be attained when the direction of rotation of the shaft 31 is reversed. The hereinbefore described mounting for the pump 33 provides a means whereby the direction of rotation of the pump may be readily kept the same. It is only necessary to remove the pinion 36, take out the stud bolts passing through the holes 45 into the wall 42, loosen the 115 pipe connections 46, 47 a predetermined extent, and then rotate the pump 180 degrees so that the end 35 of the pump shaft will assume the position of the end 34 as viewed in Fig. 3. The pinion 36 is then keyed to the end 35 and the stud bolts for holding the pump in position are replaced. The pump is then in the proper relation to the shaft 31 so that the latter may be rotated in the reverse direction. The particular 120 mounting of pump 33 is illustrative and it 125 130

is obvious that other mountings utilizing the same fundamental principles will come within the spirit and scope of the invention.

5 In case the pump 33 fails to operate for any reason, the centrifugal pump formed in the cover plate 26 is designed to provide sufficient pressure to lubricate the eccentric at least to such an extent as to prevent damage to the rotating parts should the crusher 10 continue in operation. If the centrifugal pump is of sufficient strength to raise oil up to the top of the inner eccentric surface 11 this oil will pass through the passages 80, 15 81 and as before described will reach the annular well formed by the walls 24, 25. Inasmuch, however, as no oil is being drawn into the pipe 46 the excess oil finds its way 20 into the central well 23 between the wearing ring 22 and the gear 20.

The connection of the rotary pump 33 and the centrifugal pump 26 in series whereby they may assist each other in normal operation is a considerable factor in increasing 25 the reliability of the lubricating system inasmuch as, should the rotary pump fail, the centrifugal pump which it is practically impossible to put out of operation, will furnish sufficient lubrication to prevent damage 30 to the crusher, although of course, ordinarily the lubrication by the centrifugal pump alone may not be quite so efficient as when the system operates normally.

It should be understood that it is not 35 desired to limit the invention claimed to the exact details of construction herein shown and described, for obvious modifications will occur to a person skilled in the art.

It is claimed and desired to secure by 40 Letters Patent:

1. A crusher comprising a vertical shaft, an eccentric associated with said shaft, a horizontal gear for rotating said eccentric, a cover plate for said gear, said plate being 45 provided with radial passages the outer ends of which open upwardly, and with a central opening on its under side communicating with said radial passages.

2. A crusher comprising a vertical shaft, 50 an eccentric associated with said shaft, a horizontal gear for rotating said eccentric, a cover plate for said gear; the lower end of said shaft, said eccentric, said gear and said plate forming a chamber, and means 55 whereby the rotation of said plate forces oil into said chamber.

3. A crusher comprising a vertical shaft, an eccentric associated with said shaft, a horizontal gear for rotating said eccentric, 60 a cover plate for said gear, and means whereby the rotation of said plate forces oil between said shaft and eccentric.

4. The combination of a crusher comprising a crusher shaft and means for driving 65 said shaft having a bearing surface coop-

erating with said shaft, with means for lubricating said bearing surface including means for putting the lubricant under pressure, and means for receiving said lubricant under pressure and increasing the pressure 70 still further.

5. A crusher comprising a vertical shaft and an eccentric therefor, a gear operatively associated with said eccentric and a centrifugal pump associated with and positively 75 driven by said gear for lubricating said shaft and eccentric.

6. A crusher comprising a vertical shaft, a gear operatively associated with said shaft and eccentric, a cover plate for said gear, 80 and means whereby said cover plate acts as a centrifugal pump for lubricating said shaft.

7. The combination of a crusher comprising a crusher shaft and means for driving 85 said shaft, with an oil circulating system including a pump driven by one part of said driving means and another pump in series with said first pump, driven by another part of said driving means. 90

8. The combination of a crusher comprising a vertical crusher shaft, a horizontal gear for driving said shaft, and a substantially horizontal shaft drivingly connected to said gear, with an oil circulating system 95 including a gear-pump driven by said horizontal shaft in series with a centrifugal pump driven by said gear.

9. The combination of a crusher comprising a vertical crusher shaft, an eccentric associated with said shaft, an outer bearing for said eccentric, a gear for driving said eccentric, and a substantially horizontal shaft drivingly connected to said gear, with an oil circulating system including a gear-pump 100 driven by said horizontal shaft in series with a centrifugal pump driven by said gear for forcing oil up between said shaft and eccentric, down between said eccentric and outer bearing and over said gear. 110

10. The combination of a crusher comprising a vertical crusher shaft, a horizontal gear for driving said shaft, and a substantially horizontal shaft drivingly connected to said gear, with an oil circulating system 115 including a gear-pump driven by said horizontal shaft in series with a centrifugal pump driven by said gear and means whereby the direction of rotation of said gear pump may be maintained normal when the 120 direction of rotation of said horizontal shaft is reversed.

11. In combination with a reversible crusher driving shaft, a gear driven by said shaft, a rotary pump driven by said gear, a support for said pump and means whereby said pump may be turned 180 degrees on its support so that it will be driven by said gear in its normal direction when the direction 125 of rotation of said shaft is reversed. 130

12. In combination with a reversible crusher driving shaft, a gear driven by said shaft, a pinion meshing with said gear, a rotary pump having a shaft disposed parallel to said driving shaft, said shaft being provided with means for operatively associating said pinion therewith at either of its ends, a support for said pump, means whereby said pump may be rotated 180 degrees 60
- 5 10 with respect to said support about an axis perpendicular to the center of said shaft, whereby either end of said pump shaft may be connected to said pinion.
13. A crusher comprising a crusher shaft, 15 an eccentric associated with said shaft, a gear for driving said eccentric, a wearing ring upon which said gear is supported, a bottom plate for supporting said ring and forming an oil well, and means forcing oil 20 into said well whereby oil will be forced between said wearing ring and said gear.
14. A crusher comprising a crusher shaft, an eccentric associated with said shaft, a crusher driving shaft drivingly connected 25 with said eccentric, a bottom plate for said crusher forming an oil well, and means for forcing oil into said well to lubricate said eccentric, including a pump driven by said crusher driving shaft whereby said pump is 30 rendered accessible without removal of said bottom plate.
15. A crusher comprising a crusher shaft, an eccentric associated with said shaft, an outer bearing for said eccentric, a bonnet including a cylindrical portion internally telescopically associated with said eccentric and 35 having a transverse flange extending over said bearing member, and a dust ring surrounding said shaft and extending over said bonnet.
- 40 16. In combination with a reversible crusher driving shaft, a bearing for said shaft, a bearing-housing having a wall provided with an opening, a pump adapted to be driven by said shaft, said pump having a casing provided with a cylindrical extension journaled in said opening.
17. In combination with a reversible 45 crusher driving shaft, a bearing, a bearing-housing having a pair of substantially parallel walls, provided with co-axial openings, a pump adapted to be driven by said shaft and disposed between said walls, said pump having a casing provided with a cylindrical extension journaled in one of said openings, the other end of said casing extending 50 through the other opening and provided with means whereby said casing may be fastened to the adjacent wall.
18. In combination with a reversible 60 crusher driving shaft, a gear driven by said shaft, a rotary pump driven by said gear, a support for said pump and means whereby said pump may be turned 180 degrees so that it will be driven by said gear in its normal direction when the direction of rotation 65 of said shaft is reversed.
19. In combination with a reversible crusher driving shaft, a gear driven by said shaft, a rotary pump driven by said gear, a support for said pump, said support having a recess in which said pump is disposed whereby said pump may be rotated 180 degrees and relocated in said recess so that it will be driven by said gear in its normal 70 direction when the direction of rotation of said shaft is reversed.
20. A crusher comprising a crusher shaft, an eccentric associated with said shaft, an outer bearing for said eccentric, a sleeve closely surrounding but out of contact with said shaft and mounted on said eccentric, and a transverse flange on said sleeve extending over said bearing. 75
21. In combination, a shaft, rotatable 80 means having a bearing surface coacting with said shaft, said means including a closure for the end of said shaft forming a chamber, said closure having a lubricant inlet, and means operating through centrifugal forces generated by the rotation of said 85 rotatable means to cause lubricant entering said chamber to be placed under pressure therein. 90
22. In combination, a shaft, rotatable 95 means having a bearing surface coacting with said shaft, said means including an eccentric and a closure for the end of said shaft forming a chamber, said chamber having a lubricant inlet comprising a passage 100 way having a radial component whereby rotation of said means causes lubricant entering said chamber to be placed under pressure therein, the space between said shaft and said bearing surface forming the sole 105 outlet for said chamber.
23. The combination of a crusher comprising a crusher shaft and means for driving said shaft having a bearing surface co-operating with said shaft, with means for 110 lubricating said bearing surface including means for putting the lubricant under pressure, and means for receiving said lubricant under pressure and urging it along said bearing surface. 115

In testimony whereof, the signature of the inventor is affixed hereto.

RAY C. NEWHOUSE.
